Primary Examiner — Nathan M Johnston(74) *Attorney, Agent, or Firm* — JCIP Global Inc.(57) **CLAIM**

The ornamental design for a base of medical use injection needle, as shown and described.

DESCRIPTION

FIG. 1 is a perspective view of a base of medical use injection needle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the base of medical use injection needle represent unclaimed portions of the claimed design and form no part of the claim.
